ALBERT E. GREENE, OF SEATTLE, WASHINGTON.

ELECTRIC FURNACE.

Application filed February 28, 1919, Serial No. 279,776. Renewed June 1, 1926.

My present invention relates to electric furnaces and more particularly to electric furnace electrode holders and to improved shell, door, and roof construction.

5 One object of my invention is to provide an electric furnace with an improved form of electrode holder in the form of a vertically operating trolley engaging the surfaces of a vertical I-beam with an insulated electrode clamp adapted to hold an electrode on the end of the trolley arm.

Further objects of my invention relate to a special arrangement of end door openings in a horizontal cylindrical shell, with provision for an end in the shell comprising a flat surface for a door to abut; also to a construction of roof and roof frame, having special advantages in a short arch which lessens the expansion of the roof and greatly 15 lengthens the life thereof; and also to an elongated shaped melting chamber having top electrodes entering in a row through the roof and an end door providing accessibility to the chamber and visibility to practically 20 any part thereof.

One feature of my invention relates to the combination of the trolley with trolley wheels which engage the inner surfaces of an I-beam and in this way serve to keep the 25 electrode holder arm in both vertical and horizontal alignment.

Another feature of my invention relates to a means of adjusting the length of the trolley arm for the purpose of moving the 30 electrode nearer or farther from the vertical I-beam guide for the trolley.

Another feature of my invention relates to a means of adjusting the horizontal position of the electrode contact clamp whereby 35 the position of the electrode may be varied in a horizontal direction at right angles to the axis of the trolley arm.

Another feature of my invention relates to the details of the construction of the 40 electrode contact clamp, whereby a simple means is provided for tightening or loosening the electrode contacts for the purpose of permitting the electrode to slide down through the contact.

Another feature of my invention relates to the construction of the electrode contact 45 proper whereby it may be water-cooled; and whereby contacts of different sizes suitable for making contact with electrodes of different diameters may be used in the same contact clamp, so that if it is necessary to

change the size of electrode used on the furnace, a contact of the proper diameter for the changed electrode may be quickly substituted for the previously used contact 60 in the same clamp.

These and other features of my present invention will now be described.

In the drawings Figure 1 is an end elevation of a rolling cylinder type of electric 65 furnace embodying my present invention; and Figure 2 is a back elevation of the furnace shown in Figure 1.

Figure 3 is a side elevation of an electrode holder and electrode and vertical I-beam 70 guide embodying my present invention; Figure 4 is a plan view of the holder shown in Figure 3; and Figure 5 is a sectional elevation along the line AA of Figure 3;

Figure 6 is a bottom view of a modified 75 form of electrode holder arm embodying my present invention; and Figure 7 is a side elevation of a portion of an electrode holder arm and contact clamp shown in Figure 6.

Figure 8 is a side elevation of the end 80 of the movable jaw of one form of contact clamp embodying my present invention; and Figure 9 is a sectional elevation view through the line BB of Figure 8, showing both the solid jaw and the movable jaw of 85 this contact clamp.

Referring to Figures 1 and 2, my improvements will now be described; 1 is the cylindrical shell of the furnace; 2 indicates the dished, concavo-convex ends of the cylindrical shell; 3 is the spout; 4 indicates the I-beams, which serve as vertical guides for

the trolley member to operate in; 5 is an electrode; 6 is the trolley frame, constituting the trolley arm also in this modification of 95 my invention; 7 is the contact clamp which serves to clamp the electrode 5 between the contacts proper which conduct the electric current to the electrode; 8 is the insulation between the clamp and the end of the trolley 100 arm 6; 9 indicates the trolley wheels, the upper of which engages the inner surface of the flange of the I-beam toward the electrode and the lower trolley wheel engages the inner surface of the farther flange of the I-beam.

A cable 10 operating over sheave wheels 11 serves to raise or lower the holder by being wound or unwound on a drum 12. The furnace is provided with a roof which is removable; 13 indicates the roof frame 110 arches which hold the front and back castings 14 together. The end castings 15 serve

to hold the bricks together lengthwise of the roof. The brick arch in the roof is shown partly in section at 16. The outline of the inside of the furnace chamber is shown by 5 the dotted line 17. Door frame castings 18 are placed at either end toward the outwardly dished head of the furnace shell. The doors which may be lined with refractory brick are shown at 19. A lever 20 is 10 adapted to raise or lower this door and is pivoted on the supporting angle 21; a counter-weight 22 is attached to this arm. The furnace is adapted to roll over on a track riveted to the lower portion of the shell as 15 shown at 23, which serves to keep the shell in alignment on rails 24. The shell may be tilted by any means such as a connecting rod 25 operating through the pin 26, which is held in a casting 27 attached to the furnace 20 shell.

Referring now to Figures 3, 4 and 5; several improvements embodied in this modification of my invention will now be described. 30 is an electrode; 31 is the solid 25 jaw of the contact clamp and 32 is the movable jaw of this contact clamp, 33 is the insulation between the solid jaw 31 and the member 34 which forms the end of the electrode holder arm; 35 is a vertical bolt insulated from the metal parts of both the jaw 30 and the parts of the electrode holder arm 34; insulating washers are shown at 36 and 37; 38 is an insulated bolt through a vertical surface of the clamp jaw 31 and the 35 member 34; the two surfaces of the clamp are at approximately right angles to each other and the construction here provided gives materially increased strength to the insulated joint; insulating washers 39 are 40 provided for this bolt 38 also. 40 is the holder arm proper and in a particular modification of my invention shown in this figure, this arm consists of a pipe; 41 is a member fitted to the end of the pipe 40 and may consist of a T pipe fitting. For example it may be screwed to the end of the pipe 40; the member 34 provides a vertical surface for one insulated surface of the contact clamp and also provides a top horizontal surface 45 for the other insulated surface of the contact clamp; the member 34 fits on the top and bottom of the T pipe fitting; the bolt 35 clamps together the several members through which it passes, in such a manner as to prevent them from movement, for example, the top surface of the pipe fitting and the adjoining surface of the member 34 may be grooved to prevent the member 34 slipping around the axis of the bolt 35. The trolley 50 sides are shown at 42; these provide bearings for the trolley wheels 43 above and 44 below. There are two top wheels 43, one on each side of the I-beam, each wheel engaging the surface toward the electrode; and 55 there are two lower wheels 44, each engag-

ing the opposite surface of the I-beam; the trolley sides 42 are bolted together with bolts 45 and clamp the pipe 40 by means of two members 46 and 47, which fit over the pipe 40. The length of the trolley arm may 70 be increased or diminished by loosening these bolts 45 and sliding the arm out or in of the contact members 46 and 47.

Referring to Figure 5 which is a section through the line AA of Figure 3 and which 75 shows the construction of the electrode contacts proper, 50 indicates these contacts, which may be constructed of copper; for example, copper castings. Each contact covers about 90° to 120° of the circumference of 80 the electrode as indicated in the plan view shown in Figure 4. These contacts are provided with hollow cavities which may be water cooled and the inlet and outlet to this cavity is shown at 51; each contact is provided with an extension 52 which serve for connecting the flexible leads which conduct the current to the contact; each contact is also provided with an extension 53 which serves to connect the two contacts together 90 by means of a suitable flexible jumper shown in Figure 4 at 54. In certain instances where it is desired not to use flexible connections leading directly to the contact, then solid copper bars may be connected directly 95 to the extensions 53 on one side of the holder as shown in plan in Figure 4.

The means of clamping the contacts together on the electrode is shown in Figures 3 and 4 for this modification of my invention. The mechanism consists of an eye-bolt 60 fitting over a cylindrical portion of the lever 61. An eccentric hole is located in this cylindrical portion of the lever 61 whereby the movement of the lever arm serves to 105 transmit movement to the eye-bolt 60 in similar manner to the operation of any eccentric lever; the other end of the eye-bolt 60 is provided with two nuts 62, one of which is on one side of the movable jaw 32 and the other nut being on the other side of this jaw 32. A bolt 63 serves as a pin to operate the eccentric lever 61 and the eye-bolt 60. When the lever is thrown in one direction the movable jaw will be brought closer to the solid jaw 31 and when the lever 61 is thrown in the opposite direction the movable jaw will be open, since the nuts on the eye-bolts serve to move the movable jaw along with the eye-bolt itself. The mechanism thus described serves to open the jaws of the clamp and permit the electrode to be moved upward or downward between the contacts. A special feature of this mechanism is the combination of the eccentric movement with the nuts operating on the threads of the eye-bolt 60; thus when the eccentric lever does not give sufficient clamping action the inside nut on the bolt 60 may be loosened and the outside nut may be 110 115 120 125 130

tightened, thus providing an additional means of adjustment for the jaws of the clamp.

The inner surfaces of the contacts 50 are formed to fit the diameter of the particular size of electrode for which the contact is made. Contacts may be made with different diameters of the inner surfaces and yet with approximately the same diameters for the outside surfaces of these contacts which fit in the jaws of the contact clamp. When the difference in the size of the electrode is so great that an undesirable opening of the jaws results, then the movable jaw 32 which is pivoted on a bolt or pin 64 may be moved out to an outer hole 65 and in this manner provide for increased diameter of electrodes. The water cooling cavity in these clamps shown in Figure 4 at 66 fits into the opening 67 in the jaw 30. The arrangement shown makes it possible to interchange contacts of different diameters.

In Figs. 6 and 7, a modified holder arm is shown, consisting of a T-shaped member 71. This arm is provided with a top horizontal surface shown at 72 and the bottom view of which is shown in Figure 6. Insulation is shown at 73 on this top surface, separating it from the corresponding horizontal surface of the contact member 74. The member 71 is also provided with a flat end 75 which serves to hold an additional insulating member 76 which insulates a corresponding vertical surface of the contact 74 from the arm 71. Two bolts 77 extend through the horizontal surfaces of the arm and clamp, and these bolts 77 are insulated from both members by suitable insulating bushings not shown and by insulating washers 78. The vertical surfaces are also held together by bolts 79 which are likewise insulated by insulating bushings not shown and by insulating washers 80. The construction shown here provides an exceedingly simply and strong method of holding the contact member to the arm member and yet providing adequate insulation at these surfaces.

In Figures 8 and 9 I have shown a modified form of clamping mechanism adapted to the change in the relative position of the movable jaw with respect to the solid jaw; in these figures there is shown a screw member 91 which is threaded and which is provided with a bolt head 92 through which operates a lever 93. A nut 94 serves to hold the screw in place with respect to the jaw member 97. A special nut 95 is provided in the other jaw member 98 and is constructed with pins 96 which form a part of a nut 95 and which rests in grooves in the member 98. A cap 99 on each end of this special nut serves to hold it in place with respect to the jaw 98 but permits of movement about the axis of these pins. The screw 91 may

be revolved by means of the lever 93 and the special nut member 95 serves to move the jaw 98 with respect to jaw 97. The lever 93 may slide through the head 92 on the screw 91.

With reference to Figures 3 and 4, it will be noted that the solid jaw of the contact clamp may be rotated about the axis of the bolt 35 by loosening the nut on this bolt and in this way the horizontal alignment of the electrode may be varied; the horizontal alignment of the electrode may be further varied inwardly or outwardly by the movement of the pipe arm 40 inwardly or outwardly; and the arrangement thus provides a universal adjustment of the location of the electrode.

The arrangement of the door openings into the furnace chambers as shown in Figures 1 and 2 constitutes a special feature of my present invention. The door frames in Figs. 1 and 2 consist of castings which are fitted to the ends of the cylindrical shell, that is, to the dished heads. The door frames provide an outer flat surface 101 against which the door 19 may operate, the arrangement being such that when closed the doors may be sealed by mud or clay. The arrangement here provides a door at each end of the shell, and access is thereby had to any part of the lining of the furnace. When both doors are open inspection may be readily made of the bath and lining. The opening through the spout may be made sufficiently large for the removal of slag through the spout.

The flat portion of the end of the shell need not be a casting but may be a flat end of the metal plate of the shell proper, and the door opening may be through this. The advantage of this construction is that the whole length of the inner chamber is visible through the end door, whereas in a round furnace such as the usual Heroult construction, it is practically impossible to see the walls and banks of the furnace immediately adjacent to the doorway. The furnace chamber is elongated and is covered by a short arch roof, the end of the arch resting on the top surfaces of the lining of the chamber. Through this roof are holes for electrodes in a row parallel to the axis of the cylindrical shell. The short arch greatly simplifies the construction of the roofs and adds materially to the life thereof.

The I-beams 4 shown in these figures may be very simply attached to the cylindrical shell since there is no other fitting in the way located at the back of the cylindrical shell. I-beam guides similar to these may of course be attached to any kind of movable or stationary electric furnace and serve to hold trolleys such as already described. The I-beams in these figures are held together by means of a suitable structural

member such as channel 102 at the top of the I-beams.

The roof frame constitutes another important feature of my furnace construction. 5 It is constructed with two surfaces 14 which are adapted to take the arch brick forming the roof of the furnace without the necessity of cutting these brick; that is, the surface 14 of the front and back members of the 10 roof frame have the same angle as the surfaces of the brick of the arch at the place where the brick adjoins the members 14. The bricks of the roof are held together lengthwise of the roof by the angle members 15 shown in section in Figure 2. The members 14 are further connected by the arch members 13 which may be steel castings which also facilitate lifting off the roof from the furnace shell proper.

20 It should be noted that the construction which provides vertical I-beams as guides for the electrode holder trolleys has the special advantage of simplicity in construction and at the same time is adapted to permit the removal of the roof frame so that when desired the furnace may be charged through the top. Thus the roof frame shown in Figures 1 and 2 may be lifted and moved forward and thus removed from the furnace, it being only necessary to raise the electrodes in the holders sufficiently above the top of the furnace to allow the frame to be lifted off. The construction of the roof frame may be modified by cutting off the tops of the dished ends of the furnace along the line 103, if desired. Altho I 25 have shown trolley wheels as engaging only the inner surfaces of the I-beams, it is understood that I do not limit myself to such construction and the wheels may be located in any convenient place and may operate on any or all of the surfaces of the I-beams.

30 What I claim is;

1. An electrode crane for an electric furnace, said crane comprising a vertically extending I-beam, a trolley member slidably mounted thereon, an arm attached to said trolley and extending outwardly therefrom and carrying an insulated electrode clamp for holding an electrode, and means of adjusting the elevation of said trolley along said I-beam.

2. An electric furnace electrode mechanism comprising a vertically mounted I-beam, a trolley member for operating vertically while engaging the surfaces of said I-beam, means for raising or lowering said trolley member along said I-beam, and an electrode holder attached by means of an arm to said trolley member whereby an electrode held in said holder may be raised or lowered.

3. An electric furnace electrode holder comprising an upright I-beam, an arm extending laterally from said I-beam, clamp-

ing mechanism carried by that arm remote from said I-beam, for holding an electrode in upright position, trolley wheels between the other end of said arm and said I-beam in position to engage the four inner opposing surfaces of said I-beam to guide said arm and electrode along upright rectilinear paths of travel, and means for lifting and lowering said arm along said I-beam to adjust the elevation of said electrode.

4. An electric furnace electrode holder comprising an upright I-beam, a trolley member comprising two upper trolley wheels and two lower trolley wheels in position to engage the flanges of said I-beam, a supporting arm carried by said trolley member, clamping mechanism carried by said supporting arm in position to hold an electrode, means for insulating the clamping mechanism from said supporting arm, and means for lifting or lowering said trolley member together with said supporting arm and said clamping mechanism to adjust the elevation of said electrode.

5. An electric furnace electrode holder comprising an upright I-beam, an arm extending laterally from said I-beam, clamping mechanism carried by said arm for holding electrode, means on said arm for engaging the four inner opposing surfaces of the 95 said upright I-beam in position to effect rectilinear adjustment of said arm when moved relatively to said I-beam, and means for lifting or lowering said arm together with said clamping mechanism and said electrode.

6. An electric furnace electrode trolley arm comprising a vertical trolley, two trolley wheels adapted to engage the flanges of an I-beam in the direction in which the trolley arm extends from the I-beam, and two lower trolley wheels adapted to engage the opposite inner flanges of the I-beam, and a clamping member adapted to hold an electrode at the end of the trolley arm, and means of insulating the trolley arm from the clamping member.

7. An electric furnace electrode crane for an electric furnace, said crane consisting of a vertically mounted I-beam, a horizontal arm extending outwardly from said I-beam, and means of raising or lowering said arm on rollers engaging surfaces of said vertical I-beam.

8. An electric furnace electrode holder, 120 comprising an I-beam mounted so that its axis is normally vertical, an outwardly extending electrode supporting arm, rollers for engaging the surface or surfaces of said I-beam whereby the electrode supporting member may be raised or lowered while the I-beam and rollers are in engagement.

9. In an electric furnace electrode holder the combination of two trolley members one on each side of a vertical beam along which 130

- said trolley moves, and an outwardly extending arm having an electrode holding member on the outer end of said arm, and means of bolting the arm between two members attached to said trolley sides, one or more members being slotted, whereby the longitudinal adjustment of the arm in towards or out from the trolley may be made.
10. An electric furnace electrode holder comprising a vertically operating trolley member engaging the surface of an upright guide beam, an arm extending outwardly from said trolley member, an electrode holding member on said arm, and means for adjusting the position of the electrode held thereby in a direction parallel to the axis of said arm.
11. An electric furnace electrode holder for an electric furnace comprising an upright support, an arm connected to said support for guidance along the latter while held thereby in approximately horizontal position, means for holding an electrode, and means for adjustment of said electrode to and from said upright support.
12. An electric furnace electrode holder comprising a support having upright spaced-apart bearing surfaces, an arm having a plurality of branches extending therefrom to said bearing surfaces, means carried by said arm for holding an electrode, and mechanism for adjusting the position of said arm along said support.
13. An electric furnace electrode holder comprising a vertically operating trolley member, an arm extending laterally from said trolley member, an electrode holder mounted on said arm and means for adjusting the position of an electrode held thereby so as to move the electrode horizontally in a direction parallel to the arm axis or in a direction at right angles thereto.
14. An electric furnace electrode holder comprising a vertically operating supporting arm extending in a general horizontal direction, electrode holding means mounted on said arm and means for adjusting the position of an electrode held thereby in a direction at right angles to the arm axis.
15. An electric furnace electrode holder comprising a trolley member, a supporting arm extending laterally therefrom, clamping mechanism for holding an electrode in upright position, means for pivotally connecting said clamping mechanism on the outer end of said arm to permit adjustment of said clamping mechanism and said electrode in horizontal planes and to either side of the axis of said arm, means for insulating said clamping mechanism from said arm, and means for holding the clamping mechanism in adjusted position on its upright axis of pivotal movement relative to said arm.
16. An electric furnace electrode holder comprising a trolley member, a supporting arm extending laterally therefrom, means for supporting said arm for adjustment in the direction of its axis relatively to said trolley member, and electrode clamping mechanism pivotally connected to the outer end of said arm for swinging movement relative thereto on an upright axis.
17. An electric furnace electrode holder comprising a trolley member, a laterally extending arm, means for supporting said arm in horizontal position and for adjustment in the direction of its axis relatively to said trolley member, means for holding said arm in adjusted position relative to said trolley member, electrode clamping mechanism pivotally connected to the outer end of said arm for swinging movement relative thereto on an upright axis, means for insulating said clamping mechanism from said arm, and means for holding the clamping mechanism in adjusted position relative to said arm on either side of the axis of said arm.
18. In an electrode holder the combination of two trolley members one on each side of a vertical beam along which said trolley moves, and an outwardly extending arm having an electrode holding member on the outer end of said arm, and means of bolting the arm between two members attached to said trolley sides, whereby the longitudinal adjustment of the arm in towards or out from the trolley may be made.
19. An electrode holder for an electric furnace comprising an upright member, an arm connected to said upright member for guidance along the latter and held thereby in approximately horizontal position normally, means on said arm for holding an electrode, said arm having two clamping members for holding a longitudinally adjustable part of said arm between said clamps.
20. An electric furnace electrode holder comprising a vertically operating trolley member engaging the surface of an upright guide beam, an arm extending outwardly from said trolley, said arm comprising a tubular member adjustably mounted on said trolley to move inwardly or outwardly, an insulated contact clamp on the outer end of said arm, whereby the location of the electrode in the direction of the arm may be adjusted.
21. An electric furnace electrode holder comprising an approximately horizontal arm, an end piece on said arm having a vertical pin therethru, a U shaped piece mounted on said arm end pivoted about said pin, and an electrode holding member attached to but insulated from said U piece, whereby the position of the electrode in a direction at right angles to the longitudinal axis of said arm may be adjusted.
22. The means for clamping two movable members of an electric furnace electrode holder to clamp an electrode between them,

- said means comprising a vertical pin through the outer end of one of said members, a boss mounted eccentrically on said pin, a strap member around said boss, a threaded bolt member attached to said strap and extending through the other movable clamping member and held in relation thereto by nuts, and means for adjusting the position of said eccentric boss.
- 10 23. An electric furnace electrode holder comprising two clamping members mounted on an arm and hingeably connected to each other for clamping an electrode between, and positive means of opening or closing 15 said hinged clamping device members, said means comprising an eccentric lever mechanism mounted on one of the clamping members and adjustably connected to the other clamping member through an eccentric rod, 20 whereby quick positive movement of the clamps is possible.
24. In an electric furnace electrode holder for clamping an electrode, the combination with two movable clamping members of an 25 eccentric mechanism for opening and closing the clamping members, said mechanism comprising an eccentric rod adjustably fixed to one of said clamping members and an eccentrically mounted member on the other 30 clamping member for engaging said eccentric rod, and means of adjusting said eccentrically mounted member to regulate the opening between the clamping members.
25. An electric furnace electrode holder 35 mechanism for opening and closing the jaws of an electrode clamp, said mechanism comprising a rod threaded at one end and adjustably connected to one of the jaws and eccentrically mounted at the other end on 40 the other jaw, and a lever for operating the eccentric mechanism to open or close the jaws.
26. An electric furnace electrode holder mechanism for opening and closing two jaw 45 members of an electrode clamp, said mechanism comprising an eye bolt, threaded at one end and engaging a threaded nut member mounted on one of the jaws, the eye of said bolt engaging an eccentrically mounted boss 50 on the other jaw, and means of turning said eccentrically mounted boss to adjust the jaws.
27. An electric furnace electrode holder mechanism for opening and closing two jaw 55 members of an electrode clamp, said mechanism comprising a screw threaded bolt member adjustably connected to one jaw member between nuts on said bolt, and an eccentrically mounted boss on the other jaw engaging 60 said bolt member to move the same, and means of operating said boss on its axis.
28. In combination, an electric furnace electrode holder comprising two clamping members, means for closing or opening the 65 space between said clamping members, and a contact member inside each clamping member between it and the electrode, said contact members each comprising a conductor for electricity and having a surface of contact of less than 180 degrees of arc to 70 contact with said electrode, and a lug extending up above the clamping members and providing space for attaching a conductor thereto.
29. In combination, an electric furnace 75 electrode holder comprising a clamping device for holding an electrode and two separate contacts held between said clamping device and said electrode, each of said contacts having water cooling means. 80
30. In combination with an electric furnace electrode holder, a clamping mechanism comprising two contact clamping members adapted to clamp an electrode between two replaceable circuit contacts one on each 85 side of the electrode, said contacts being removable from said clamping members and replaceable by other contacts when the size of electrode is changed.
31. An electric furnace electrode holder 90 comprising a supporting member and an electrode holding member separated by an insulating joint, said joint comprising two surfaces of abutment in different planes with insulating material between in both 95 planes.
32. An electric furnace electrode holder comprising a supporting member and a clamping member, an insulated joint between, said joint having two opposing surfaces separated by insulating material in one plane, and two other surfaces likewise separated by insulating material in another plane, and insulated bolts holding each two 100 surfaces together. 105
33. In combination, an electric furnace electrode holder, comprising an arm, a clamping member attached to said arm for holding an electrode, and an insulating joint between said arm and said clamping member comprising two insulating surfaces one horizontal and the other vertical and means of holding the said arm and clamping member in place while maintaining them insulated from each other. 110 115
34. In combination, an electric furnace electrode holder arm having a flat end surface and a flat top surface adjoining, insulating material on these two surfaces, an electrode clamping member having corresponding surfaces abutting the said end and top surfaces of said arm but with the insulating material between. 120
35. In combination an electric furnace electrode holder comprising a clamping member attached to the end of a supporting arm but insulated therefrom by a vertical layer of insulating material, insulated bolts holding the opposing surfaces of said clamping member and arm against each other, and 125 130

said clamping members and arm each having a horizontal surface of abutment with insulating material between.

36. An electric furnace electrode holder comprising an arm and an insulated clamping member attached to said arm, said clamping member comprising a relatively fixed member and a member hinged thereto, a threaded eye bolt adjustably connected at its threaded end to one of the members between nuts on said bolt and at the other end a cylindrical boss within said eye bolt but mounted eccentric of said eye bolt, whereby the relative position of the fixed and movable clamping members may be adjusted

either by adjustment of the nuts or of the eccentric member.

37. In combination with an electric furnace electrode holder, an arm carrying an electrode clamping member, a vertical insulating partition and a horizontal insulating partition between corresponding vertical and horizontal surfaces of said arm and clamping member, said surfaces being held against the partitions by insulated bolts. 25

In witness whereof I hereunto subscribe my name this 21st day of February, A. D. 1919.

ALBERT E. GREENE.
